DESIGN FOR A NEBULIZER OR THE LIKE

Arthur W. Pitts, Tacoma, Wash.

Application April 8, 1946, Serial No. 128,384

Term of patent 14 years

(Cl. D83—1)

To all whom it may concern:

Be it known that I, Arthur W. Pitts, a citizen of the United States of America, residing at Tacoma, in the county of Pierce and State of Washington, have invented a new, original, and ornamental Design for a Nebulizer or the like, of which the following is a specification, reference being had to the accompanying drawing, forming part thereof.

Figure 1 is a side elevational view of a nebulizer or the like, showing my new design, with the bulb and connecting tube shown in dotted lines in Figure 3 omitted for convenience of illustration.

Figure 2 is a transverse sectional view thereof taken on line 2—2 of Figure 1.

Figure 3 is a perspective view thereof.

The dominant features of my design reside in the portions of the nebulizer or the like shown in full lines.

I claim:

The ornamental design for a nebulizer or the like, as shown and described.

ARTHUR W. PITTS.
